UNITED STATES PATENT OFFICE.

FREDERICK A. PETERSEN, OF NEW YORK, N. Y.

FIREPROOF FLOOR AND CEILING.

Specification of Letters Patent No. 12,642, dated April 3, 1855.

To all whom it may concern:

Be it known that I, FREDERICK ALEXR. PETERSEN, of the city, county, and State of New York, have invented a new and useful 5 Improvement in Fireproof Floors and Ceilings for Buildings; and I do hereby declare that the following is a full, clear, and exact description thereof, reference being had to the accompanying drawings, making part of 10 this specification, in which—

Figure A, is a cross vertical section of my improved floor and ceiling. Fig. B, represents a ground plan, and Fig. C, a bottom view of the under and scratched or scored 15 surface of one of the tile tubes. Fig. D, is a cross vertical section on a reduced scale of my improved floor and ceiling, and Fig. F, is a cross section of one of the tile tubes representing the mode of applying registers 20 for the escape of heated air, and for ventilation.

The nature of my invention consists in forming fire proof floors and ceilings of flanged metallic beams combined with tile 25 tubes formed with the bottom nearly flat and the top arched, and with the sides adapted to rest on the lower flanches of the beams so that the tile tubes resting on, and being supported by, the iron beams without 30 lateral thrust, afford a substantial support for concrete filling above to form a level surface for the floor.

In the accompanying drawings *i*, represents a series of iron beams supported in 35 the usual manner by having their ends inverted in, and resting on the walls. These beams are flanged at the lower edges, as at *j*, *j*, and if desired in like manner at the upper edges; and may be placed at any de- 40 sired distance apart, say not to exceed five feet from centers. The beams being thus formed and arranged I take tile tubes made of terra cotta, clay, glass, metal or other suitable substance which admit of being 45 molded and baked, or cast, of the required form, and which will present the required strength. They should be cast or molded of an arching form at the top *k*, the sides being connected with a flat bottom or chord *l*, of 50 the arch, as this form presents the required strength to admit of extending from beam to beam and to occupy but little space vertically. The sides along the lower edges are formed with rebates, as at *m*, to fit into the flanches of the beams and rest thereon, and

to bring the lower surface on or below a level with the lower surface of the beams.

The lower surface of the tile tubes is scratched as represented at *n*, for the purpose of receiving the brown coat of plaster which adheres firmly thereto by reason of entering the furrows. These tile tubes may be made in lengths equal to the length of the beams, or in shorter sections properly put together; and after they have been properly 60 inserted between the beams the upper surface can be filled up, as at *o*, *o*, with concrete, cement, plaster or other suitable substance to form the required surface to receive tiles or a wooden floor. If these tubes 65 are to be employed for the additional purpose of ventilating, holes *h*, *h*, can be made in the top and bottom, to which registers can be adapted in the usual manner for the 70 passage of air; but by connecting these tubes 75 with hot air flues in the walls heated air can be made to circulate through them, or any portion of them, and discharged into the 80 apartments through suitable registers *g*, fitted to holes in the floor or tiles, and thus 85 present a more efficient mode of heating and ventilating buildings than any other known construction. And again, in fitting up the 90 spaces *o*, *o*, between the arched surface of the tubes and the beams, the required room 95 can readily be left for water and gas pipes. In this way floors and ceilings can be produced presenting advantages not to be attained by any other known mode of construction, such as being equally fire proof 100 with arches of masonry, without occupying so much vertical space in the building, and without the necessity of heavy walls, such as are required to resist the thrust of arches, for by the form of the tubes they will 105 neither thrust against the beams nor against the walls. Ample and convenient room is obtained for water and gas pipes, with an important advantage that by carefully grouting with cement or plaster between the tubes and the arches, in case the water pipes should burst, the ceilings below will be protected against injury from the flow of water. It will save the expense and labor of lathing and scratch coating the ceiling. It admits of a ready, convenient and efficient 110 system of ventilation both from the ceiling and floors, and through the center of the rooms instead of the sides as heretofore; and what is of great importance it presents

an easy and efficient mode of heating apartments.

I do not wish to be understood as limiting myself to the special form of the beams and tubes, and the kind of filling between them so long as the same result is attained by merely formal variations.

What I claim as my invention and desire to secure by Letters Patent is—

10 The method substantially as herein de-

scribed of making fire proof floors and ceilings by means of metallic flanged beams in combination with tile tubes interposed between and resting on the flanches of the beams, and filled in above, all substantially as, and for the purpose specified. 15

F. A. PETERSEN.
